UNITED STATES PATENT OFFICE.

BEN D. BARTON, OF LANSING, MICHIGAN.

BELT PULLEY AND TIGHTENER.

1,394,705.

Specification of Letters Patent.

Patented Oct. 25, 1921.

Application filed January 24, 1920. Serial No. 353,843.

To all whom it may concern:

Be it known that I, BEN D. BARTON, a citizen of the United States, residing at Lansing, in the county of Ingham and State 5 of Michigan, have invented certain new and useful Improvements in Belt Pulleys and Tighteners, of which the following is a specification.

This invention provides a guide adapted 10 for use in connection with a drive belt to enable the latter to be easily, quickly and conveniently adjusted to a tractor or analogous source of motive power generally used on the farm for driving machinery of various kinds and for different purposes.

Tractors having the drive belt at the end are preferable to those having the belt pulley at the side, but difficulty is experienced in placing the belt in position and maintaining proper tension of the belt.

The present invention enables the end arrangement of belt pulley to be successfully and conveniently utilized on all types of tractors and motive appliances adapted for 25 farm use.

The drawings illustrate the preferred embodiment of my invention. However, it is to be understood that in adapting the same to meet different conditions, various changes 30 in the form proportion and minor details of construction may be resorted to without departing from the nature of the invention as claimed hereinafter.

Referring to the drawings hereto attached:—

Figure 1 is a detail view in side elevation of an end portion of a tractor provided with a belt guide attachment embodying the invention,

40 Fig. 2 is an end view of the parts illustrated in Fig. 1 showing the drive belt in section.

Corresponding and like parts are referred to in the following description and indicated 45 in both views of the drawings.

The tractor designated by the numeral 1 may be of any construction and the same is typical of any motive power adapted for use on the farm. The numeral 2 designates 50 the drive shaft of the engine and 3 the belt pulley attached thereto. The drive shaft 2 is longitudinally disposed and projects beyond the end of the tractor and the projecting end receives the belt pulley 3.

55 In accordance with the present invention, a pair of frame members 4 and 5 are pro-

vided at each side of the tractor and the members are secured thereto in any convenient and substantial way. The members consist of bars which may be of any form. 60 In the preferred construction, angle bars are utilized because of the strength afforded, consistent with lightness of structure. The members 5 constitute supports and the members 4 braces. The supporting members 5 65 have their lower ends stepped upon a close piece 6 of the tractor frame work. The brace members 4 have hooks 7 at their lower rear ends which engage lateral extensions 8 of the frame work of the tractor. It will 70 thus be understood that the attachment may be quickly and easily braced in position or removed as required. Castings or metal fittings 9 are attached to the upper ends of the members 4 and 5 and are formed with eyes 75 which receive a transverse shaft 10. The castings or fittings 9 have their eye portions provided with set screws 11 whereby the parts 4 and 5 and 10 are secured in the required position when properly adjusted. 80 Guide pulleys 12 are loosely mounted upon the transverse shaft 10 and receive the runs of the drive belt 13 which passes around the belt pulley 3 and transmits motion from said pulley to the machine to be driven. The 85 pulleys 3 and 12 are so disposed that a vertical plane passing through the center of the pulley 3 will touch the rear face of the pulley 12 thereby enabling the upright portions of the drive belt 13 to occupy a perpendicular 90 position as indicated most clearly in Fig. 1. The runs of the drive belt passing over the guide pulleys 12 are prevented from lateral displacement by means of guides 14, which consists of vertically disposed pins 95 and sleeves mounted thereon. One guide 14 is disposed between the two runs of the drive belt and a guide 14 is located exteriorly to each of the runs. This is indicated most clearly in Fig. 2.

From the foregoing taken in connection with the accompanying drawings it will be understood that the invention provides an attachment which enables the successful and convenient use of a tractor or other motive power having the drive belt pulley disposed at the end thereof. When it is desired to place the drive belt in position an end portion is passed over the guide pulleys 12 and doubled so that the bight may receive the 110 drive pulley 3. To tension the drive belt the tractor or other motive power is backed

or moved in a direction to increase the distance between the tractor and the machine or part to be driven with the result that the drive belt is stretched and tensioned to the requisite degree. The construction is such as to admit of the attachment being easily, quickly and conveniently placed in position or removed as may be required.

10 Having thus fully described my invention what I claim as new and desire to secure by Letters Patent, is:—

15 1. A belt guide attachment of the character specified comprising a pair of members adapted to be disposed at each side of a tractor or analogous motive power, the members of each pair being angularly disposed so that one member constitutes a support and the other a brace, metal fittings at the 20 upper ends of the members each of the fittings including an eye, a transverse shaft supported in the eyes of the metal fittings, means for securing the shaft to the fittings and retaining the parts in adjusted position, 25 and guide pulleys loosely mounted upon the shaft.

2. A belt guide attachment of the character specified comprising a pair of members adapted to be disposed at each side of a 30 tractor or analogous motive power, the mem-

bers of each pair being angularly disposed so that one member constitutes a support and the other a brace, metal eye fittings at the upper ends of the members, a transverse shaft supported in the eyes of the fittings, 35 set screws threaded into the eyes of the fittings for securing the shaft and members in the required adjusted position, guide pulleys loosely mounted upon the shaft, and belt guides secured to the shaft and located between and exterior to the guide pulleys to prevent lateral displacement of the runs of the drive belt.

3. A belt guide attachment of the character specified comprising a plurality of members, a shaft carried by the outer ends of said members, pulleys loosely mounted upon said shaft, vertically arranged rollers mounted upon said shaft between and to the side of said pulleys for facilitating the retaining 50 of a belt upon said pulleys and means for detachably securing said members to a tractor or analogous motive power.

In testimony whereof I affix my signature in presence of two witnesses.

BEN D. BARTON.
